UNITED STATES PATENT OFFICE

91,135

DESIGN FOR A LAUNDRY BAG

Edna M. Gilligan, Oakland, Calif.

Application September 5, 1933. Serial No. 49,201

Term of patent 7 years

To all whom it may concern:

Be it known that I, EDNA M. GILLIGAN, a citizen of the United States, and a resident of the city of Oakland, county of Alameda, State of California, have invented a new, original, and ornamental Design for Laundry Bag, of which the following is a specification, reference being had to the accompanying drawing, forming part thereof.

Referring to the drawing:

I claim:

The ornamental design for a laundry bag, as shown.

EDNA M. GILLIGAN.
